CLAIM

The ornamental design for a kit for storing and displaying a string of characters as shown and described.

DESCRIPTION

FIG. 1 is a left, front, top isometric view of a kit for storing and displaying a string of characters showing our new design, the right, back, and bottom isometric view being identical;

FIG. 2 is a left side view thereof, the right side view being identical; and,

FIG. 3 is a left, front, top, exploded isometric view thereof, the right, back, and bottom, exploded isometric view being identical.

The broken lines shown in the drawings represent portions of the kit for storing and displaying a string of characters that form no part of the claimed design.
